UNITED STATES PATENT OFFICE.

PETER OSTENDORF, OF VIENNA, AUSTRIA.

SIEMENS-MARTIN FURNACE.

Application filed August 29, 1921. Serial No. 496,688.

(GRANTED UNDER THE PROVISIONS OF THE ACT OF MARCH 3, 1921, 41 STAT. L., 1313.)

To all whom it may concern:

Be it known that I, PETER OSTENDORF, a citizen of the German Empire, and resident of Vienna, Austria, have invented a certain 5 new and useful Improved Siemens-Martin Furnace (for which I filed applications in Germany, Apr. 19, 1918, Patent No. 313,781; Austria, May 21, 1918, Patent No. 89,151; Hungary, May 24, 1918, Patent No. 76,694; 10 France, May 20, 1920, Patent No. 515,746; Poland, Sept. 15, 1919; Czechoslovakia, June 19, 1919, Patent No. 5,061; Yugoslavia, Aug. 17, 1921), of which the following is a specification.

15 This invention relates to Siemens-Martin furnaces, or open-hearth furnaces, of the kind in which the furnace is combined with gas-producers built integral, or united, with its frontal ends or heads. Concerning these 20 furnaces, it has already been proposed to connect the white-heat zone, of the gas-producers, that is to say: that zone in which the coal is completely burned or gasified with the 25 hearth space so that the radiant heat of this zone acts directly upon said hearth space and increases its temperature. The white-heat or 30 gasification zone of the gas-producers has been connected, for the purpose in question, by special slots with the hearth space of the Siemens-Martin furnace, but this means entails considerable disadvantages for the practical service because then each furnace head 35 has three channels located above, or below, each other, viz, the air channel, the gas channel, and the connecting channel between the said white-heat zone and the hearth space. Building a furnace head having three channels above one another offers great 40 difficulties and, moreover, such a head is far more exposed to the danger of burning away than is the case with the usual furnace head having but the simple gas and air-channels.

Now according to the present invention, the said connecting channel between the white-heat zone of the gas producer and the hearth space of the Siemens-Martin furnace is made to serve not only for the direct transference of the heat of said white-heat zone to and into the furnace hearth, as is the case 45 in the known constructions of the furnaces of the kind in question, but also for leading the heating gases into the said hearth space. Thus, also in this case the direct utilization 50 and exhaustion of the gasification heat for

the purpose of increasing the furnace hearth 55 temperature is rendered possible, but without a special gas channel between the gas producer and the furnace-hearth, that special channel being now dispensed with. This simplification offers the further advantage that the temperature of the gas mixed 60 in the gas channel with the products of combustion of the gas producer and being exposed to the high temperature of the gasification or white-heat zone is considerably increased. 65

The air being highly pre-heated in heat accumulators is preferably introduced in a well known manner into the hearth from above in oblique direction and under a 70 rather high pressure in order to hold the hot gas down upon the bath and to permeate the compact gas current whereby at the same time the gas and the air are thoroughly mixed and a complete combustion is obtained. 75

In order to make my invention more clear, I refer to the accompanying drawing, in which similar letters denote similar parts throughout the several views, and in which 80 Figure 1 is a vertical longitudinal section through a furnace constructed according to this invention; Figure 2 is a horizontal section in line A—B of Figure 1; and Figure 3 is a vertical transverse section in line 85 G—H of Figure 1.

Below the hearth space are disposed the heat accumulators *b b* in which the air is pre-heated and which are provided with slides or the like (not shown) for controlling the entrance and the discharge of the air. The accumulators *b* are connected by channels *c* with channels *d* provided in the furnace heads and opening from above in oblique direction into the hearth space *a*. 90 The channels *d* serve for conducting the hot air into said space *a* and upon the bath. 95

In front of each furnace head is a gas producer *e* of any suitable construction. The gas therein produced is conducted by exterior horizontal pipes *f f* into gas collecting chambers *g g* provided in the furnace walls. These chambers are connected with a gas conduit *k* extending horizontally in transverse direction through the furnace 100 masonry and communicating with the hearth *a* by means of passages *l l*. The connection between the chambers *g g* and the 105

outer ends of said channels *k k* is effected by elbows *i i* containing each a valve *h* for controlling or regulating the quantity of gas admitted to the hearth. The passages *l l* open into the hearth at as deep a point as possible in order to effect a very intimate contact of the gas with the bath.

According to the present invention the heating gas and the flame projecting forth from the white heat gasification zone *m* of the gas producers mix in the passages *l l* whereby the gas is highly heated. Owing to the width of the passages *l l* also the radiant heat of the gasification zone of the gas producer contributes in heating not only the gas passing through the passages *l l*; but also, although in a lesser degree, the hearth *a*, whereby an extraordinarily hot working of the furnace is obtained.

In order to conduct the gas coming from the two gas producers into the furnace always at one side only, the chambers *g g* of the one furnace head are connected with the chambers *g g* of the other furnace head by top pipes *n n* so that if, for instance, the valves *h h* of the righthand furnace head are closed, the gas may be led to the lefthand furnace head, and vice versa, the one

head receiving then the gas from both gas producers. The righthand passage *l*, need 30 not be shut if the gas enters the space *a* through the lefthand passage, or vice versa, the less so as the white-heat existing in the respective gas-producer shall act upon the bath, as already explained.

The reversal of the valves *h* is effected simultaneously with the reversal of the air valves (not shown).

I claim:—

An open hearth furnace comprising in 40 combination, a melting room, a gas generator adjacent said melting room, the wall between said melting room and said generator having only two superposed channels extending therethrough, one of said channels 45 connecting the lower part of said generator with the lower part of said melting room, while the other channel extends obliquely downwards into the upper part of the melting room.

In testimony whereof I have affixed my signature.

PETER OSTENDORF.

In the presence of—

B. TOLKENDORF,
C. HÄRBEL.
